UNITED STATES PATENT OFFICE.

WILLIAM W. WATSON AND JOHN G. CARLSON, OF JAMESTOWN, NEW YORK, ASSIGNEES
TO WATSON MANUFACTURING COMPANY, OF JAMESTOWN, NEW YORK, A CORPO-
RATION OF NEW YORK.

METALLIC ROLLER.

1,092,464.

Specification of Letters Patent.

Patented Apr. 7, 1914.

Application filed August 7, 1912. Serial No. 713,846.

To all whom it may concern:

Be it known that we, WILLIAM W. WATSON and JOHN G. CARLSON, citizens of the United States, residing at the city of Jamestown, in the county of Chautauqua and State of New York, have invented certain new and useful Improvements in Metallic Rollers, of which the following, taken in connection with the accompanying drawing, is a specification.

The invention relates to sheet metal rollers for shelving and particularly for book shelves; and the object of the improvement is to provide a simple and exteriorly smooth construction having strength, lightness and stability, so that they will roll easily when heavy books are passed over them and will not injure the books; and the invention consists in the construction and combination of the parts as shown in this specification and the accompanying drawings and pointed out in the claim.

In the drawings, Figure 1, is a side elevation of the improved roller. Fig. 2 is a lengthwise sectional view of the improved roller showing the manner of attaching the sheet metal central tubular portion to the ends. Fig. 3 is a sectional view of one of the unattached ends, as shown attached in Fig. 2; and Fig. 4 is a side elevation of said end, showing the annular groove therein. Fig. 5 is an end elevation of one of the rolls.

Like numerals of reference refer to corresponding parts in the several views.

35 The numeral 10 designates the sheet metal tubular central portion of the roller, which may be a seamless or a brazed tube or may be a strip of sheet metal bent in tubular form. The seamless or brazed tube is preferred.

40 The numeral 11 designates the end piece to which the tubular portion 10 is attached. The end pieces 11 are preferably made of metal and have their ends 12 slightly rounded and a central pivot or journal 13. A

45 groove 14 is provided around the outer periphery of the end piece 11, care being taken that the wall 15 be at an inward angle toward the ends of the roller. The bottom of the groove 14 is rounded, as shown in Figs. 2, 3, and 4, to receive the tubular end of the central portion 10 which is turned inwardly

on itself in groove 14 in the following manner: A rounded die is provided to receive the end piece 11 and the tubular portion 10 is then inserted within the hole of the die until the end strikes the inclined wall 15. The sheet metal tubing under heavy pressure will seek the line of least resistance and coils inwardly upon itself along the wall 15 and as it passes inwardly necessarily wedges 60 against the walls of the groove 14 thereby firmly holding the tubular end within the groove 14 and giving a smooth outer surface at the joint between the parts which can not mutilate or mar the books. The portion 17 65 of the end 11 within the tubing 10 is diminished around its periphery the thickness of the tube 10 so as to make a smooth exterior for the joint.

We claim as new—

A metal roller of the type set forth, consisting of a hollow tube having substantially right angular inwardly curled ends of substantially U-shape in cross section, and a pair of end members for the respective tube 75 ends, said end members having annular grooves of sufficient depth to receive said U-shaped ends, the outer walls of which grooves are directed inwardly and extend toward the outer ends of said end members 80 to provide angular abutments against which the outer legs of the U-shaped ends of the tube engage, the opposite walls formed by said grooves also providing abutments which engage with the inner legs of the U-shaped 85 ends, and act to wedge said legs in said grooves, the free extremities of the inner legs of the U-shaped ends terminating at substantially the inner surface of the tube, the periphery of the end members beyond the 90 grooves being substantially in alignment with the tube periphery whereby to provide a roller possessed of approximately uniform diameter throughout its length.

In testimony whereof we have affixed our 95 signatures in the presence of two witnesses.

WILLIAM W. WATSON.
JOHN G. CARLSON.
